UNITED STATES PATENT OFFICE.

WILLIAM LOUIS BESSOLO, OF SAN DIEGO, CALIFORNIA.

PIPE-WRENCH.

1,318,047.

Specification of Letters Patent. Patented Oct. 7, 1919.

Application filed December 1, 1917, Serial No. 204,840. Renewed May 5, 1919. Serial No. 235,029.

To all whom it may concern:

Be it known that I, WILLIAM LOUIS BESSOLO, a citizen of the United States, and a resident of San Diego, in the county of San Diego and State of California, have invented a certain new and useful Improvement in Pipe-Wrenches, of which the following is a specification.

My present invention relates generally to pipe wrenches, and more particularly to that type of pipe wrench including a shank, and a flexible object-encircling jaw having an elongated link connecting the same at one end with the shank, the shank being provided with means with which the free end of the flexible jaw is adjustably engaged in order to hold the same in connection with the engaged object.

My invention further proposes the use of certain additional features, such as readily manipulated means whereby to release the free end of the movable jaw in order to permit of more ready quick detachment thereof from the object engaged thereby.

In the accompanying drawings:

Figure 1 is a side elevation of one form of my improved wrench illustrating the movable jaw engaging means of the shank in adjustable relation with the latter;

Fig. 2 is a detail cross section taken there-through substantially on line 2-2 of Fig. 1;

Fig. 3 is a detail perspective view of the catch adjusting piece;

Fig. 4 is a side elevation of a slightly modified form in which the catch of the shank is rigid therewith;

Fig. 5 is a plan view thereof;

Fig. 6 is a plan of the inner face of a portion of the movable jaw;

Fig. 7 is a side view partly broken away and in section of another slightly modified form, and,

Figs. 8 and 9 are sectional views taken respectively on lines 8-8 and 9-9 of Fig. 7.

Referring now to these figures, it will be noted that in each of the forms illustrated the shank of the wrench, one end of which forms a handle, is provided at its opposite end with a transversely extending toothed catch member providing for its engagement in a readily and freely adjustable manner with the teeth of the outer surface of the flexible jaw, one end of the latter of which is connected by spaced parallel side links to the head end of the shank, through the space

between which links the free end of the movable jaw may be extended.

Thus, in Figure 1, the shank appears generally at 10, forming a handle generally indicated at 11 at one end and having an enlarged head 12 at its opposite end transversely of the latter, from which is extended the catch member 13 having a series of teeth 14 upon its outer surface. The flexible jaw has one end thereof in the form of a curved arm 15 from which extend a plurality of flexibly connected and jointed links 16, the outer surfaces of the several links of the arm 15 having teeth 17 for engagement with the teeth 14 of the catch member 13, and the inner surfaces thereof having series of teeth for engagement with the object to be grasped. One end of the flexible jaw opposite the arm 15 is pivotally connected to the outer ends of a pair of spaced side links 18, the inner ends of which are pivotally connected at 19 to the head 12 of the shank so as to provide for the desired leverage in shifting movement between the flexible jaw and the shank, the head of which forms a rigid jaw, to bring the movable jaw in firm gripping relation with the object to be engaged.

According to the form seen in Figs. 4, 5, and 6, in which the shank generally appears at 10^a with its handle 11^a at one end and its enlarged head 12^a at the opposite end, the arm 15, before described at one end of the movable jaw may be dispensed with if desired and the entire jaw formed of links 15^a having their outer surfaces provided with teeth 17^a for engagement with the catch member 13^a disposed transversely of the head 12^a of the shank and having their inner surfaces provided with object-gripping teeth 16^a. As shown in the figures last mentioned, moreover, in which the links 18^a connect the movable jaw at one end with the head 12^a in a flexible manner for the before mentioned purpose, the catch member 13 is rigidly connected to the headed end of the shank, while in the form shown in Figs. 1, 2, and 3 the catch member 13 is pivotally connected at one end at 20 to one side of the head 12 and has its opposite free end bearing against a spring 21, the inner end of which is seated in the opposite side of the head so as to normally thrust the free end of the catch member away from the head. In this way the catch member is normally connected

upon and maintains close engagement between the same and the teeth of the flexible jaw, and in connection therewith I provide means whereby the operator may, without 5 releasing the handle 11, pull the catch member 13 toward the head and away from the engaged portion of the flexible jaw so as to free the latter. The means described consists of a catch adjusting member 22 in the 10 form of a plate extending along one side of the head end of the shank 10 and provided intermediate its ends with a longitudinal slot 23, through which slot the screw or other fastening member 24 extends into the mate- 15 rial of the shank 10 so as to limit relative longitudinal movement of the member 22, the outer end of the latter of which projects outwardly beyond the head 12 and has a hook shaped extremity 25 engaging the free 20 end of the catch member 13, utilizing the last tooth of the latter for this purpose. The inner end of the adjusting member 22 has an angular outstanding portion 26 forming a thumb piece, by means of which the operator 25 grasping the handle may readily move the adjusting member 22 toward him and thus retract the catch member 13 from engaged position.

According to the form shown in Figs. 7, 30 8 and 9, the shank 10^b has a handle 11^b and a head 12^b at one side of the latter of which the catch member 13^b is pivoted, and the arms 18^b at one end of the movable jaw 17^b are longitudinally slotted as at 16^b and ad- 35 justably connected to the head 12^b by a transverse connecting member 15^b through the slots thereof. The inner portions of the arms 18^b and the link of the jaw 17^b as well as the end arm 14^b are toothed, and the 40 outer portion of arm 14^b is also toothed to coact with the catch member 13^b as in the previously described constructions.

It is obvious from the foregoing that my invention provides a wrench which may be 45 readily manipulated in use, which consists of minimum parts, and which will be inexpensive to manufacture.

I claim:

1. A wrench comprising a shank having

a handle at one end and an enlarged head 50 at its opposite end, a catch member extending transversely of the head and provided with an outer toothed surface, a pair of spaced side links pivotally connected at their inner ends to one side of the said headed shank, and a flexible jaw pivotally connected to the outer ends of the said links, said jaw including a plurality of flexibly connected sections having inner toothed gripping surfaces and provided along their outer surfaces 60 with teeth for engagement with the teeth of the catch member, said catch member being pivotally connected at one end to the shank head, a spring upon which the opposite end of the catch member bears, and an adjusting member mounted on the shank and engaging the free end of the catch member, said adjusting member being shiftable longitudinally of the shank to withdraw the catch member from engaged position. 70

2. A wrench comprising a shank having a handle at one end and an enlarged head at its opposite end, a catch member extending transversely of the head and provided with an outer toothed surface, a pair of spaced 75 side links pivotally connected at their inner ends to one side of the said headed shank, a flexible jaw pivotally connected to the outer ends of the said links, said jaw including a plurality of flexibly connected sections 80 having inner toothed gripping surfaces and provided along their outer surfaces with teeth for engagement with the teeth of the catch member, said catch member being pivotally mounted at one end adjacent the 85 pivotal connection of the first named links with the head, a spring supported by the head and engaging the free end of the catch member to normally shift the latter away from the shank head, and an adjusting piece 90 mounted along one side of the shank and having a limited movement with respect thereto, said adjusting piece having a hook at its outer end engaging the other end of the said catch member and having an angularly bent thumb piece at its inner end adjacent the handle of the shank. 95

WILLIAM LOUIS BESSOLO.
